PEELER FOR CITRUS FRUIT OR THE LIKE

William Egge, Box 27, Heron Lake, Minn. 56137

Filed Sept. 16, 1966, Ser. No. 3,893

Term of patent 14 years

(Cl. D89—1)

FIG. 1 is a front perspective view of a peeler for citrus fruit or the like showing my new design;

FIG. 2 is a bottom perspective thereof;

FIG. 3 is a top plan view;

FIG. 4 is a side elevation;

FIG. 5 is a rear view;

FIG. 6 is a front view;

FIG. 7 is a bottom plan view.

I claim:

The ornamental design for a peeler for citrus fruit or the like, substantially as shown.
